UNITED STATES PATENT OFFICE.

ALBERT S. LAMBERT, OF BRIDGETON, NEW JERSEY.

FRUIT-JAR.

SPECIFICATION forming part of Letters Patent No. 289,276, dated November 27, 1883.

Application filed July 19, 1883. (No model.)

To all whom it may concern:

Be it known that I, ALBERT S. LAMBERT, a citizen of the United States, residing at Bridgeton, in the county of Cumberland and State of New Jersey, have invented a new and useful 5 Fruit-Jar, of which the following is a specification, reference being had to the accompanying drawings.

This invention relates to fruit-jars; and it 10 has for its object to produce a jar to which the cover may be easily and conveniently applied and secured, and from which it may be readily removed, when desired, the construction being such that the cover, when applied, shall seal 15 the jar in an air-tight manner.

To this end my invention consists in the improved construction and arrangement of parts, which will be hereinafter fully described, and particularly pointed out in the claims.

20 In the drawings hereto annexed, Figure 1 is a perspective view of my improved fruit-jar with the cover in position. Fig. 2 is a top view of the jar with the cover removed. Fig. 3 is a perspective view of the cover detached. Fig. 25 4 is a vertical sectional view of the jar and cover; and Fig. 5 is a side view of the jar and cover, illustrating the method of applying the latter.

The same letters refer to the same parts in 30 all the figures.

A in the drawings designates the jar, the neck of which is provided, below the top rim, with an annular flange, B, supporting a rubber band or gasket, C, which serves as packing. The flange B is provided on diametrically 35 opposite sides with vertical notches D, which are gradually beveled or sloping, so as to form lugs E, projecting radially from and integral with the body of the jar.

40 F is the cover, which has an annular rim or flange, G, adapted to rest upon the gasket or packing C. The upper side of the cover is provided, near its edge, with an annular groove or recess, H, in which is seated a ring, I, provided on diametrically-opposite sides with upward-projecting lugs or ears J, in which a bail or handle, K, is hinged, as shown. The upper side of the ring I is beveled or sloping from each of the lugs J down to the opposite one, so 45 as to form a double cam or wedge. The cover F is also provided with a central upwardly-projecting stud, L, having a transverse perforation, M, in which is seated a wire bail, N,

formed of spring-wire, and the ends or legs of which are bent downward over the edge of the 55 cover. The lower ends of the legs O are bent so as to form hooks P, facing in the opposite direction. The bail N serves to hold the ring I in position in the groove H, and also serves for attaching the cover to the jar, as will be 60 presently described.

In operation the beveled notches D enable the hooked legs O, when the cover is placed in position upon the jar, to pass down over the flange B. By giving the cover a slight turn 65 the hooks P may then be thrown into engagement with the lugs E, thus connecting the cover with the jar. By means of the handle or bail K the ring I may then be turned, thus causing its beveled or wedge-shaped sides to force the 70 ends of the bail N in an upward direction and tighten the cover upon the jar. The fastening is now absolutely secure, and the jar may be conveniently carried by the handle K. To remove the cover, the operation is simply reversed.

I claim as my invention and desire to secure by Letters Patent of the United States—

1. The combination, with a fruit-jar, the neck of which is provided on diametrically- 80 opposite sides with radially-projecting lugs, of a cover having a central upwardly-projecting transversely-perforated stud, and a spring-wire bail seated in the same, and having down-turned ends, the ends of which are bent so as 85 to form hooks, substantially as herein set forth.

2. A cover for fruit-jars, having an annular recess or groove, a ring seated in the said groove, and provided on diametrically-opposite sides with ears or lugs having a bail or handle, the 90 upper side of said ring being beveled or wedge-shaped from each lug down to the other one, and a transverse spring-bail having down-turned ends bent so as to form hooks, all as set forth, in combination with a jar the neck 95 of which is provided on diametrically-opposite sides with radially-projecting lugs, substantially as and for the purpose set forth.

In testimony that I claim the foregoing as my own I have hereto affixed my signature in 100 presence of two witnesses.

ALBERT S. LAMBERT.
